PISTON

Curt Retschy, Winterthur, Switzerland, assignor
to Sulzer Frères, Société Anonyme, Winter-
thur, Switzerland

Application February 1, 1939, Serial No. 254,081
In Switzerland January 29, 1938

10 Claims. (Cl. 123—193)

This invention relates to a piston primarily intended for use in an internal combustion engine. In the particular form shown, the piston is not cooled by any positive cooling means. The invention has for one object to provide in a piston construction means for resisting high heat and for conducting and dissipating that heat. Another object is to provide a built-up piston construction in which the several parts are so joined together as to resist distortion. A still further object is to provide a built-up piston in which the several parts are so shaped and joined together as to provide an adequate path for the transfer of the heat from the zone of combustion. Another object is to provide a piston made of a number of parts so arranged that they are positively secured together along the piston axis or along lines parallel with that axis and are relatively free for relative radial motion.

Other objects will appear from time to time throughout the specification and the claims.

The invention is illustrated more or less diagrammatically in the accompanying drawing, wherein:

Figure 1 is a longitudinal section through the piston and a portion of the engine cylinder;

Figure 2 in its left hand is a top plan view of the plate which forms the upper surface of the piston, and in its right hand section is a bottom plan view;

Figure 3 is a top plan view of the piston body or bell.

Like parts are designated by like characters throughout the specification and the drawing.

1 indicates a portion of a cylinder wall. A liner 2 is positioned therewith. A cylinder head 3 is mounted upon the liner and defines in part the combustion chamber. A ring-like member 4 is positioned outside of the cylinder head 3 and is secured in position upon the cylinder jacket 1 by nuts and bolts 5 or by screws or otherwise. 6 are cooling spaces formed in the cylinder head and 7 are cooling spaces formed between the cylinder head and the jacket or ring member 4. Cooling fluid is circulated through the spaces 6 and 7 from any suitable source and by any desirable means.

The particular form of engine here illustrated is of the injection type and includes a valve 8 and an inlet nozzle 9. Fuel may be supplied to the valve and nozzle from any desired source and is discharged into the combustion space. While the invention is illustrated as applied to an injection engine, it may be applied to other types of engines and in fact a piston of the type

here shown may be used in many places where it is desirable or necessary to provide for the resistance of the piston to heat and to provide for the dissipation of heat from the piston. The use of the present invention is, therefore, not limited to an engine.

The main upper surface of the piston is formed by a highly heat-resistant plate 11, which overlies substantially the whole surface of the piston with the exception of that which is defined by the ring-like member 10, which is shaped to overlie and in part to support the uppermost piston ring. The main piston body or bell comprises a member 12 having a depending integral skirt 13, within which is positioned a number of piston rings 14. As above mentioned, the uppermost of the piston rings is in contact with the member 10. Positioned within the hollow defined by the piston face 12 and the skirt 13 is a core 15 of material having high heat conductivity. One suitable material is aluminum. This core serves to conduct heat from the plate 11 to the member 12 and thence to the skirt 13.

As a means of securing the plate 11, the piston 12 and the core 15 together, a central bolt 16 is used. It may be threaded at its upper end as at 17 to engage a correspondingly threaded socket or depression 17—*a* on the under side of the plate 11. At its outer end the bolt 16 is threaded to receive a nut 18, which holds the parts together and in the particular form here shown contacts a washer or ring 19 positioned against or seated within a suitable depression in the core 15.

As shown in Figure 1, the parts illustrate the condition when cold and it will be seen that there is a clearance 20 between the core 15 and the skirt 13. The parts are free for relative radial movement, which will occur on expansion and contraction, and the core 15 cannot transmit heat directly to the skirt 13 until it has expanded sufficiently under the influence of heat to come into contact with the skirt.

As a further means for holding the parts generally in suitable position, a number of attaching bolts 21 is provided. These bolts serve merely the purpose of holding the surface plate 11 to the portion 12 of the piston. Clearance *y* is provided between the bolts and the member 12. A number of additional and longer bolts 22 is also provided and these secure the core 15 in position within the piston 12. Clearance *y* is provided about the bolts 22 just as it is provided about the bolts 21. A spacing sleeve 23 is provided about the bolts 21 and is of material preferably

more or less self-lubricating. Nuts 24 are positioned upon the bolts 21. A sleeve 23—a of similar material is provided about the bolts 22, and nuts 24—a secure the bolts and the sleeves in proper position. In general, the bolts 21 and 22 hold the plate 11 in place and prevent its distortion when it is heated. In particular, they prevent buckling or warping of this plate, but because of the play between them and the portion 10 of the piston and between them and the core 15 they permit radial movement of the parts, one with relation to the other. The nuts 24, for example, are turned on only by hand and thus do not rigidly clamp the parts together.

15 The upper surface of the piston member 12 has only a limited surface of contact with the under face of the plate 11. Thus there is provided on the upper or outer face of the member 12 a number of raised ring-like portions 25. As shown, 20 these are preferably in the form of concentric circles but they might take other shapes. They might also be formed on the bottom surface of the plate 11 instead of being formed on the portion 12, or they might, if desired, be formed on 25 the opposing faces of both the member 11 and the member 12.

The remainder of the piston and connecting rod construction need not be shown. In general, they may comprise a ring-like portion 26, which 30 is held in place in the piston assembly by the bolts 22; and they may include other parts 27, shown only in part, and the necessary bearings and bearing supports for connection to the connecting rod. These parts are omitted because 35 they form no essential part of the present invention and are not necessary for an understanding of it.

Although I have shown an operative form of my device, it will be understood that many changes 40 in the form, shape and arrangement of parts might be made without departing from the spirit of my invention, and I wish that my showing be taken as in a sense diagrammatic.

The use and operation of this invention are 45 as follows:

The piston may be used in any place where it is desirable to have a piston so arranged that it can dissipate heat adequately and without distortion. As shown, it is applied to an internal 50 combustion engine of the injection type.

The piston is formed of the several parts shown and already described, and these are secured together as shown. The piston is positioned in a cylinder and is secured to a connecting rod in 55 any desired manner.

In the association shown herewith, when the piston is cold, the parts are to some degree reduced in size to provide the clearances shown. As heat develops in the use of the engine, a certain amount 60 of expansion occurs. The heat first affects the heat receptacle or heat-protecting plate 11, which preferably consists of high-temperature-resistant steel. A certain amount of expansion occurs as this member is heated. Since the plate 11 is only 65 in limited contact with the upper surface of the main piston bell 12, heat is conducted from the plate to the bell only along these limited paths of contact. In the particular form shown, these paths are largely defined by the raised portions 70 25 of the upper surface of the bell 12. Some heat will, of course, be conducted through the central bolt 16 and also through the bolts 21. The upper surfaces of the bolts are, as shown in Figure 1, shaped to provide the same general sort of limited contact with the heat-resistant plate 11.

Because the plate and the bell and the core 15 are connected only on the line of the piston axis, they are freed for relative radial movement, which occurs, of course, on expansion and contraction of one or another of these parts.

Heat received by the plate 11 and conducted through the members 25 to the upper surface of the bell 12 is then conducted by direct contact to the core 15; and because the core is ordinarily in contact with the piston skirt 13 when the parts 10 are fully heated, heat from the core is transmitted directly to the skirt of the piston.

Should any tendency toward buckling develop in any of the parts, and particularly in the plate 11, that tendency is resisted by the bolts 21, which 15 prevent buckling. They are ordinarily screwed in only lightly—as, for example, by hand—and they are also provided with the lubricating or sliding sleeves 23 so that they freely carry the thrust of the plate and, therefore, hold the plate free 20 for radial expansion and contraction while preventing buckling.

In use, because of the construction shown, the heat-protecting plate 11 is raised to a sufficient 25 temperature largely because the heat dissipated from the plate 11 must pass through the limited contact members 25; and the heat dissipation from the plate 11 to the other parts of the built-up piston is thus slower than it would be if the parts were all in full contact with each other.

Because of the limited contact between the plate 11 and the bell 12, as the plate 11 is heated from above during engine operation, there occurs at first from the plate 11 downwardly only an axial 30 heating current or flow. As the parts expand under the influence of heat, additional contacts occur between the various parts, and the path through which the heat flows is increased by these 35 added contacts. This process continues until all of the members which make up the piston are 40 in contact with each other and are carrying their loads uniformly.

I claim:

1. In combination in a built-up piston, a main piston bell having an outer end member and 45 a skirt, a separate surface member of highly heat-resistant material positioned on the outer end of said piston and defining the outer end surface of the piston, and a core member of highly heat-conductive material positioned within the said piston, and means for securing the three together in heat transfer relation, said means permitting relative radial movement of the three.

2. In combination in a built-up piston, a main piston bell having an outer end member and a skirt, a separate surface member of highly heat-resistant material positioned on the outer end of said piston and defining the outer end surface of the piston, and a core member of highly heat-conductive material positioned within the said piston, and means for securing the three together in heat transfer relation, said means permitting relative radial movement of the three and preventing their axial separation.

3. In combination in a piston comprising a main bell member, having an end member and a skirt, a heat protecting surface plate attached to said piston positioned above the surface of its end member, and means positioned between 70 the opposing surfaces of the piston and the plate adapted to hold them largely out of contact, the said means comprising the sole contact between the said two surfaces, and an attachment joining the plate and the piston together, said 75

attachment adapted to permit relative radial movement of the two.

4. In combination in a piston comprising a main bell member, having an end member and a skirt, a surface plate attached to said piston positioned above the surface of its end member, and means positioned between the opposing surfaces of the piston and the plate adapted to hold them largely out of contact, the said means comprising the sole contact between the said two surfaces, and an attachment joining the plate and the piston together, said attachment adapted to permit relative radial movement of the two and adapted to hold them against axial separation.

5. In combination in a piston comprising a main bell member, having an end member and a skirt, a surface plate attached to said piston positioned above the surface of its end member, and formed of highly heat-resistant material, and means positioned between the opposing surfaces of the piston and the plate adapted to hold them largely out of contact, the said means comprising the sole contact between the said two surfaces, and an attachment joining the plate and the piston together, said attachment adapted to permit relative radial movement of the two.

6. In combination in a piston comprising a main bell member, having an end member and a skirt, a surface plate attached to said piston positioned above the surface of its end member and formed of highly heat-resistant material, and means positioned between the opposing surfaces of the piston and the plate adapted to hold them largely out of contact, the said means comprising the sole contact between the said two surfaces, and an attachment joining the plate and the piston together, said attachment adapted to permit relative radial movement of the two and adapted to hold them against axial separation.

7. In combination in a built-up piston, a piston bell, a plate positioned on the outer face of the piston and formed of highly heat-resistant

material, a core positioned within the bell and formed of highly heat-conductive material, and means positioned between the plate and the upper surface of the bell to limit the contact of the two to an area appreciably less than their total opposed areas.

8. In combination in a built-up piston, a piston bell, a plate positioned on the outer face of the piston and formed of highly heat-resistant material, a core positioned within the bell and formed of highly heat-conductive material, and means positioned between the plate and the upper surface of the bell to limit the contact of the two to an area appreciably less than their total opposed areas, and fastening means joining the several parts to each other and adapted to hold the parts against relative longitudinal movement but to permit relative radial movement of the parts.

9. In combination in a piston, a piston bell having a top plate and a downwardly depending skirt integral therewith, a heat-resistant plate positioned above and supported upon said piston bell, a core formed of a highly heat-conductive material positioned within said piston, and means positioned approximately on the line of the longitudinal axis of said piston, said means securing the plate, the piston bell and the core together; the piston bell being provided in its outer surface with a number of raised members, additional attaching means, some engaging said plate and holding it to the upper surface of said bell and others engaging said bell and holding said core in place, the parts being shaped to provide a clearance between the various parts when cold the attaching means being positioned to permit relative radial movement of the parts but to prevent relative longitudinal movement.

10. A piston in accordance with claim 3, characterized by the fact that the heat-protecting plate is attached to the skirt by screws which are underlaid with self-lubricating metal and are only slightly screwed into place.

CURT RETSCHY. 45
